UNITED STATES PATENT OFFICE.

HOSMER BLUM, OF SAN FRANCISCO, CALIFORNIA.

MIXING APPARATUS.

Application filed August 17, 1925. Serial No. 50,537.

The present invention relates to mixing apparatus of the type especially adapted for mixing beverages. It is to be understood, however, that the apparatus may be used for mixing other liquid or fluidic substances; and that the principles embodied in the invention as expressed in the claims hereto appended, may be utilized in devices whose form, proportion, and construction may differ from those of the device which is herein described and illustrated, and which should be regarded merely as a typical embodiment of the invention as adapted for mixing beverages.

An object of the invention is to provide a mixing apparatus which can be easily cleaned and kept clean, to prevent contamination of the liquid placed therein. Another object is to provide an apparatus capable of thoroughly and quickly mixing the liquids or fluidic materials placed therein by violent agitation. A further object is to prevent the violently agitated liquid from slopping or spilling. A still further object is to provide means for quickly attaching the liquid containing receptacle to and removing it from the mixing device.

In order to achieve these and other objects, I provide an apparatus which has but one moving part in contact with the liquid, and that part, preferably, has no bearings or journals into which the liquid might penetrate, and which would have to be taken apart for cleaning. This moving part is preferably a flexible diaphragm, forming a portion of the wall of the container or receptacle, and is caused to vibrate, by outside forces, to set up pulsating currents in the liquid within said receptacle.

A more complete description of a preferred embodiment of the invention will now be given, with reference to the accompanying drawings, wherein:—

Fig. 1 is a part sectional elevation of the complete mixing apparatus.

Fig. 2 is a detailed end elevation, enlarged, of one of the eccentrically mounted pitman ends.

Fig. 3 is a vertical section of one of the receptacles with its mounting.

Fig. 4 is a plan view of the receptacle.

Fig. 5 is a sectional plan taken on the line 5—5 of Fig. 3.

Fig. 6 is a vertical section of a modified form of receptacle.

In the drawings, the reference numeral 1

designates a liquid containing mixing vessel or receptacle, which may be made of glass, metal, or any other suitable material, and is preferably formed with circular cross section and outwardly flaring sides, as shown. The bottom of the receptacle 1, as shown in Fig. 3, is a flexible diaphragm 2, formed of rubber or other suitable material, which is preferably removable, and mounted in any convenient manner. For example, I have shown said diaphragm 2 as having its peripheral edge set or clamped in a ring 3, preferably metal, and said ring is clamped between a shoulder 4 formed upon an annular flange 5 secured to the lower portion of the receptacle and a plug member 6 screwed into said flange. Thus by unscrewing said plug member, the diaphragm 2 may be removed for cleaning or replacement, and when said diaphragm is in place, and the plug member screwed home, the entire assembly forms a liquid containing receptacle with a flexible bottom.

Above the flexible bottom or diaphragm 2, the receptacle 1 is provided with a partition or false bottom 7, which may be removable for cleaning, if desired, and may be secured in the position indicated in Fig. 3 by any suitable means, not shown. The false bottom 7 is formed with apertures 8, Figs. 3 and 5, to permit the liquid to pass through it, and above said apertures are positioned baffles or deflectors 9 which cause the liquid passing upwardly through the apertures 8 to enter the receptacle 1 with a swirling or tangential motion, as indicated by the arrows in Figs. 3 and 4. For this purpose, the deflectors 9 are closely contiguous to the receptacle wall at 10, and to the false bottom 11, their ends 12 being open to allow the fluid to pass through.

It will be readily understood that, if the receptacle 1 be partially filled with liquid, and the diaphragm 2 be rapidly vibrated, by any suitable outside source, said liquid will be violently agitated, and on account of the positioning of the apertures 8 and the deflectors 9, that helically and upwardly directed pulsating currents will be set up in said liquid, as indicated by the arrows in Figs. 3 and 4, thereby causing a complete and rapid mixing. In order to prevent such agitation and currents from causing the liquid to slop over the top of the receptacle 1, I may provide some suitable deflecting means, as for example a series of inclined

baffles 13, Figs. 3 and 4, secured to and projecting inwardly from the wall of said receptacle near its upper end, such baffles being positioned to re-direct the ascending helical current in a downward direction.

The bottom plug-member 6 is provided with a neck 14 and a bottom flange 15, the latter serving as a base upon which the receptacle may stand. The neck 14 is hollow, 10 and preferably interiorly tapered, as shown in Fig. 3, to adapt it for separable connection with the means for vibrating the diaphragm 2. Although any suitable means may be employed for vibrating said diaphragm, I prefer to use a pulsating air current, and as a preferred means for supplying such an air current, I have shown the apparatus illustrated in detail in Figs. 1, 2 and 3.

20 An electric or other motor 16, Fig. 1, is housed within a suitable casing 17, which may be vented as shown at 18. The top 19 of said casing is preferably secured directly to the motor 16, as shown at 20, to insure 25 rigidity, and is provided with one or more flanged cap members 21, there being two such cap members shown in Fig. 1. A flexible diaphragm 22, formed of leather or other suitable material, is placed beneath 30 each cap member 21, the edge portion of said diaphragm being clamped between said member and the casing top 19. Each diaphragm 22 is connected by a pitman rod 23 with an eccentric 24 mounted upon the 35 shaft 25 of the motor 16. The connection between the diaphragm and the pitman rod is preferably made by means of two rigid plates or washers 26 secured to said rod and clamping the central portion of the diaphragm between them. A spring 27, Fig. 40 3, may be inserted between the diaphragm 22 and the cap member 21. Each eccentric 24 is preferably provided with a ball bearing 28 for the pitman rod end, as shown in 45 Fig. 2.

The cap members 21, one of which is shown in section in Fig. 3, are formed with upstanding tubular nipples 29, exteriorly tapered to fit within the necks 14 of the receptacle bottom members 6. Thus when a receptacle 1 is fitted upon one of the nipples 29, as shown in said Fig. 3, it is not only held firmly in upright position, but a 50 communicating passage is established between the chamber 30 below the receptacle diaphragm 2 and the chamber 31 above the power diaphragm 22, so that, when the latter is vibrated by the motor 16, acting through the pitman rod 23, a pulsating air current is caused to act upon the bottom of receptacle diaphragm 2, causing it to vibrate and so agitate the liquid contained within the receptacle 1 as described above.

55 I have shown in Fig. 6 a slightly modified form of device embodying the principle

of my invention. In this construction, the receptacle diaphragm 2 is mounted in a chambered member 32 positioned to one side of the receptacle 1, and connected therewith by a tubular nipple 33, the bottom ring or 70 flange member 5' of said receptacle having a tight and rigid bottom 34. The chambered member 32 is extended upwardly in the form of a handle 36 which may be grasped conveniently, and whose upper end 75 is connected with the receptacle 1 by a brace 37, as shown. The operation of this form of the device is exactly like that of the previously described form, the vibrations of the diaphragm 2 producing pulsating currents in the liquid within the chambered member 32, which currents passing into the bottom of the receptacle 1 through the nipple 33, are directed by the deflectors 9 in 80 ascending helical paths as before.

Having thus described my invention, what I claim as new and desire to protect by Letters Patent of the United States is:—

1. A mixing apparatus comprising a receptacle having a movable wall portion, 90 means with which said receptacle is adapted for removable association for vibrating said wall portion to produce pulsations in the fluid contents of the receptacle, and means within said receptacle for directing said pulsations.

2. A mixing apparatus comprising a receptacle having a flexible member forming a portion of its wall, means with which said receptacle is removably associated for vibrating said flexible member to produce pulsations in the fluid contents of the receptacle, and means within said receptacle for directing said pulsations.

3. A mixing apparatus comprising a receptacle having a movable bottom, means with which said receptacle is adapted for removable association for vibrating said bottom to produce pulsations in the fluid contents of the receptacle, and means within 105 said receptacle for directing said pulsations.

4. A mixing apparatus comprising a receptacle, a flexible diaphragm forming the bottom of said receptacle, means with which said receptacle is adapted for removable association for vibrating said diaphragm to produce pulsations in the fluid contents of the receptacle, and means within said receptacle for directing said pulsations.

5. A mixing apparatus comprising a receptacle, a flexible diaphragm removably associated therewith and forming a bottom therefor, means with which said receptacle is associated for vibrating said diaphragm to produce pulsations in the fluid contents of the receptacle, and means within said receptacle for directing said pulsations.

6. A mixing apparatus comprising a receptacle having a movable wall portion, means with which said receptacle is asso-

ciated for vibrating said wall portion to produce pulsations in the fluid contents of the receptacle, and means within said receptacle for directing said pulsations into a helically ascending current.

7. A mixing apparatus comprising a receptacle having a movable wall portion, means for vibrating said wall portion to produce pulsations in the fluid contents of the receptacle, means within said receptacle for directing said pulsations into a helically ascending current, and means for re-directing said current downwardly.

8. A mixing apparatus including a receptacle provided near its base with a fluid passage, vibratory means for causing a rapid reciprocal flow of fluid into and from the receptacle through said passage, and means for directing the fluid flow from said passage tangentially into said receptacle.

9. A mixing apparatus including a receptacle provided with a transverse bottom wall having a fluid passage, a movable wall beneath the bottom wall for precluding the escape of fluid from said receptacle through said passage, and means with which said receptacle is removably associated for operating said movable wall to cause a rapid reciprocal flow of fluid into and from the receptacle through said passage.

10. A mixing apparatus including a receptacle provided with a transverse bottom formed with a fluid passage, a flexible diaphragm beneath said transverse bottom wall for precluding the escape of fluid from the receptacle through said passage, and means with which said receptacle is removably associated for vibrating said flexible diaphragm.

40 11. A mixing apparatus including a receptacle, a movable wall at the base thereof for precluding the escape of fluid therewith, and a ported dividing wall within the receptacle above said movable bottom wall, said receptacle provided with a tubular neck affording a communication to the underside of the movable wall.

50 12. A mixing apparatus including a receptacle provided with a movable bottom wall, a ported wall within the receptacle above the bottom wall, means associated with the ports of the ported wall for directing fluid passing upwardly therethrough tangentially into the receptacle, and means with which the receptacle is adapted for remov-

able association for rapidly moving said bottom wall to create a fluid flow through said receptacle ported wall.

13. A mixing apparatus including a receptacle provided on its inner face near its top with a plurality of angularly extended downwardly inclined directing vanes, said receptacle being provided with a movable bottom wall and a transverse ported wall above said bottom wall.

60 14. A mixing apparatus including a receptacle provided near its base with a fluid passage, a wall precluding the escape of fluid from the receptacle through said passage, and means with which said receptacle is adapted for removable association for causing a rapid reciprocation through said passage of fluid into and from the receptacle.

70 15. A mixing apparatus including a tubular base, a receptacle carried thereby and provided near its bottom with a transversely disposed ported wall, a movable member between the receptacle and the base for precluding the passage of fluid from the receptacle through said tubular base, and means for operating said movable member through said tubular base for causing a reciprocal flow of fluid to and from the receptacle through the ports of said wall.

75 16. A mixing apparatus comprising a receptacle having a movable wall portion, and means for directing a pulsating current of air against the exterior of said wall portion to produce vibrations therein.

80 17. A mixing apparatus comprising a receptacle having a flexible wall portion, and mechanism with which said receptacle is separably associated, said mechanism being adapted to direct a pulsating current of air against the exterior of said wall portion to produce vibrations therein.

85 18. A mixing apparatus comprising a casing having an aperture in its wall, means within said casing for supplying a pulsating, 100 current of air through said aperture, a receptacle adapted for separable association with said aperture, and a flexible diaphragm forming a portion of the wall of said receptacle and adapted to be vibrated by said pulsating air current.

90 In testimony whereof I have signed my name to this specification.

HOSMER BLUM.
